ATTORNEY

UNITED STATES PATENT OFFICE.

LEO MORSE, OF NEW YORK, N. Y.

DESIGN FOR A RATTLE.

58,160.

Specification for Design. Patented June 14, 1921.

Application filed January 6, 1921. Serial No. 435,521. Term of patent 7 years.

To all whom it may concern:

Be it known that I, LEO MORSE, a citizen of the United States, residing in the city, county, and State of New York, have invented a new, original, and ornamental Design for Rattles, of which the following is a specification, reference being had to the accompanying drawing, forming a part thereof.

Figure 1 is a front elevation; Fig. 2 is a rear elevation, and Fig. 3 is an edge elevation of a rattle showing my new design.

I claim:

The ornamental design for a rattle, as shown.

LEO MORSE.
